UNITED STATES PATENT OFFICE.

WALTER REISE GATLIN, OF HOPKINSVILLE, KENTUCKY.

BAG-FASTENER.

1,236,159.

Specification of Letters Patent. Patented Aug. 7, 1917.

Application filed June 9, 1916. Serial No. 102,636.

To all whom it may concern:

Be it known that I, WALTER R. GATLIN, a citizen of the United States, and a resident of Hopkinsville, in the county of Christian 5 and State of Kentucky, have invented a new and Improved Bag-Fastener, of which the following is a full, clear, and exact description.

My invention relates to paper-bag fasteners, and has reference more particularly to a fastener which constitutes reinforcing means at the mouth of the bag. The object of the invention is to provide a simple and inexpensive bag fastener which is rigid, durable, 15 and which does not permit the side of the bag to buckle.

With the above and other objects in view, the nature of which will more fully appear as the description proceeds, the invention 20 consists in the novel construction, combination and arrangement of parts as herein fully described, illustrated and claimed. In the accompanying drawings, forming part of the application, similar characters of reference indicate corresponding parts in all the views.

Figure 1 is a perspective view of an open paper bag embodying my fastener;

Fig. 2 is a similar view showing the mouth 30 of the bag covered by the flap and the flap ready to be engaged by the fastener;

Fig. 3 is a perspective view of the upper part of the bag showing the bag fastener;

Fig. 4 is a perspective view of the upper 35 part of the bag when seen from the other side from that shown in Fig. 3;

Fig. 5 is an enlarged vertical section through the bag when closed on line 5—5, Fig. 3; and

Fig. 6 is a plan view of the bag blank.

Referring to the drawings, 7 represents a blank suitable to be folded into a bag presenting at one end thereof a mouth through which merchandise may be introduced thereinto. At the edges which are to form the mouth the blank is provided with a tongue 8 and a flap 9. Both may form an integral part of the blank, as shown in Fig. 6, or they may be pasted thereto. The flap 9 is 50 to fold over the mouth of the bag along the base thereof, that is to say, on lines a—a (see Fig. 6). The tongue 8 is folded along its base on line b—b against the exterior surface of the side of which it forms part.

The end of the tongue 8 carries a pliable, 55 metal strip 10, preferably secured thereto by wrapping the end portion of the tongue about the strip, the extremity of the strip projecting out of the tongue beyond the longitudinal edges of the back. The metal 60 strip 10 is so secured to the tongue 8 as to have clearance from the edge of the flap 9 and fold against the flap 9 when the same is folded over the tongue 8 (see Fig. 2). The flap and tongue are further folded to 65 interlock, as shown in Figs. 3 and 5, whereby the tongue 8 and flap 9 will be folded on lines c—c. The projecting ends of the strip can then be bent against the other side of the bag, as shown in Fig. 4, thus 70 locking the mouth of the bag positively, the strip serving as a reinforcing member for the bag at the mouth. It will be noted that the bag is locked slightly below the mouth thereof and the edges or corners at the 75 mouth are prevented from spreading by the engagement of the ends of the strip with the edges of the bag. Thus, a sudden shift of the contents within the bag cannot open the bag. 80

Preferably a portion of the tongue 8, bound by the base line b—b and the fold c—c, may be secured to the bag with glue. That portion only serves as means for extending the metallic strip sufficiently from 85 the edge of the mouth of the bag to form a clearance between the metallic strip and the edge of the flap 9. By gluing the portion of the tongue 8 bound by the lines b—b, c—c, the bag will be reinforced at the mouth 90 by the said portion of the tongue.

I claim:

A bag of the class described having a tongue on one side of the bag depending from the mouth, a flap forming a part of 95 the bag adapted to fold over the mouth and tongue without folding the bag proper at the mouth, and a foldable metallic strip secured to the free end of the tongue, the extremities of the strip projecting beyond the 100 edges of the bag, said flap and tongue being adapted to be rolled about the strip toward the mouth of the bag when the bag is to be sealed, the projecting ends of the strip being adapted to be folded over the adjacent edges 105 of the bag and lock the folded tongue and flap to the bag.

WALTER REISE GATLIN.
